UNITED STATES PATENT OFFICE.

HAROLD MOORCROFT, OF NEW YORK, N. Y., ASSIGNOR TO AMERICAN DRESSLER
TUNNEL KILNS COMPANY, INC., OF NEW YORK, N. Y.

SAGGAR.

1,186,490.

Specification of Letters Patent. Patented June 6, 1916.

Application filed August 26, 1915. Serial No. 47,446.

To all whom it may concern:

Be it known that I, HAROLD MOORCROFT, a subject of the King of England, residing at New York, in the county and State of New York, have invented certain new and useful Improvements in Saggars, of which the following is a full, clear, and exact specification.

This invention relates to saggars or receptacles for holding articles of earthenware or pottery in a kiln for firing, and is especially designed for holding ceramic mosaic and similar small tiles.

One object of the invention is to facilitate the placing of the ware into the saggars, while other objects are to economize space and heat taken up in the kiln.

The invention will be first hereinafter described in connection with the accompanying drawings, which constitute a part of this specification, and then more specifically defined in the claims at the end of the description.

In the accompanying drawings, wherein similar reference characters are used to designate corresponding parts throughout the several views:—

Figure 1 is a perspective view of one of the containers made in accordance with this invention. Fig. 2 is a plan view of a group of these containers or saggars assembled as they are placed in a kiln, and Fig. 3 is a vertical section through two layers of saggars, showing how the bottom of each container forms the top of the one immediately below it when said containers or saggars are built up in layers in the kiln as is well understood by those skilled in this art.

My improved saggars are made of fire-clay or like material suitable for tiles, pottery and other articles manufactured which require to be fired or burnt in containers through kilns, and instead of being provided with four walls, as has been common heretofore, it is formed with a bottom 1, only one side wall 2 and only one end wall 3. When these containers are assembled in the usual manner,

as indicated in Figs. 2 and 3, the walls 2 and 3 of each container form the other two walls of adjacent containers, and the bottom of each of said containers also constitutes the top of the container immediately below it, thus making only one wall for the heat to penetrate in passing from one container or saggars to the next in order to reach the contents to be burned, as against two walls or double thickness of walls with the ordinary saggars having four walls each instead of two, as in the present case.

In order to insure the proper fitting of each saggars to the surrounding ones, so as to complete the four inclosing walls of each container when in use, I provide interlocking ribs and grooves at the corners of the walls 2 and 3. The outer ends of the walls 3 and 2 are formed with grooves 5 and 6, respectively, while the corner at the juncture of said walls has projecting ribs 7 and 8 adapted to fit the grooves 6 and 5, respectively, of the adjacent saggars.

The upper edges of the walls 2 and 3 are preferably provided with openings or notches 4 to allow free circular of hot air, but these notches or openings may be omitted. The size and thickness of the walls of the saggars may of course be varied to suit requirements of the different articles to be fired.

Having thus described my invention, what I claim as new and desire to secure by Letters Patent of the United States is:—

1. A container of the character described having walls at two sides made integral with its bottom, the other two sides being open to be closed by walls of another container placed beside the first one.

2. A container of the character described having a bottom and two side walls meeting at one corner, said walls having interlocking ribs and grooves at the juncture of said walls and at their free ends for the purpose specified.

In testimony whereof I have signed my name to this specification.

HAROLD MOORCROFT.
